CLAIM

I claim the ornamental design for a candle cover, as shown and described.

DESCRIPTION

FIG. 1 is a perspective view of a candle cover illustrating my new design;

FIG. 2 is a right side view thereof;

FIG. 3 is a left side view thereof;

FIG. 4 is a top view thereof;

FIG. 5 is a bottom view thereof; and,

FIG. 6 is a top perspective view thereof.

The broken lines in FIG. 5 represent portions of the candle cover that forms no part of the claimed design.

The broken lines in FIG. 6 are directed to an environment and forms no part of the claimed design.
